CLAIM

The ornamental design for a connector for a hurricane lamp shade, as shown and described.

DESCRIPTION

FIG. 1 is a perspective view of the connector for a hurricane lamp shade showing my new design;

FIG. 2 is a front elevational view thereof, the rear view being a mirror image;

FIG. 3 is a top plan view thereof; and,

FIG. 4 is a bottom plan view thereof.

FIG. 1

FIG. 2

FIG. 3

FIG. 4

UNITED STATES PATENT AND TRADEMARK OFFICE
CERTIFICATE OF CORRECTION

PATENT NO. : **Des. 353,684**
DATED : **December 20, 1994**
INVENTOR(S) : **Mark S. Moussa**

It is certified that error appears in the above-identified patent and that said Letters Patent is hereby corrected as shown below:

On the title page, item [54], and column 1.
Title of invention should be —Connector For A Hurricane Lamp Shade—.

Signed and Sealed this
Seventh Day of March, 1995
